Des. 178,735
Patented Sept. 11, 1956

178,735

COMBINED SUGAR PACKET AND NAPKIN DISPENSER

John E. Oberlies, Indianapolis, Ind.

Application August 24, 1955, Serial No. 37,637

Term of patent 14 years

(Cl. D44—24)

Fig. 1.

Fig. 2.

Fig. 3.

Fig. 1 is a perspective view of a combined sugar packet and napkin dispenser showing my new design;

Fig. 2 is a side elevation thereof; and

Fig. 3 is a bottom plan view thereof.

The device, when viewed from the rear of Fig. 1 is the same as appears in Fig. 1.

I claim:

The ornamental design for a combined sugar packet and napkin dispenser, as shown and described.
